(22) Filed: **Aug. 18, 2016**

CLAIM

(51) LOC (11) Cl. **24-01**

The ornamental design for an intelligent heart rate monitor ring, as shown and described.

(52) U.S. Cl.

USPC **D24/167**; D24/186; D10/39; D10/70;
D10/97; D14/344

DESCRIPTION

(58) **Field of Classification Search**

FIG. 1 is a perspective view of the intelligent heart rate monitor showing my new design.

USPC D10/30-39, 65, 70, 78, 97, 98; D11/3;
D14/138 R, 203.5, 203.6, 341, 344, 347;
